RATCHET WRENCH

Foster A. Haist, Buffalo, N. Y.

Application June 12, 1935, Serial No. 26,206

4 Claims. (Cl. 81—82)

This invention relates to a ratchet wrench and more particularly to a "two way" ratcheting socket wrench in which the axis of rotation of the socket is perpendicular to the plane of movement of the handle.

The principal object of the invention is to provide a wrench of the type which is stronger and simpler than those heretofore in use known and is, at the same time, just as smooth and positive 10 in its action. A further object of the invention is to provide a ratchet wrench of this type which will continue to operate satisfactorily even after being subjected to severe abuse and long continued use. Numerous other collateral objects 15 of the invention and solutions therefore are shown in the herein patent specification, wherein:

In the accompanying drawings:

Fig. 1 is a diminutive top plan of my improved 20 wrench.

Fig. 2 is a fragmentary, horizontal section through the head of the wrench, taken on line 2—2, Fig. 4.

Figs. 3 and 4 are fragmentary, vertical sections 25 through the head of the wrench, taken on correspondingly numbered lines of Fig. 2.

Fig. 5 is a perspective of one of the ratchet pawls and its companion dual-purpose spring.

Similar characters of reference indicate like 30 parts in the several figures of the drawings.

For purposes of illustration, only one form of the invention has been shown in the accompanying drawings, but it is obvious that considerable departures from this particular construction 35 may be made without departing from the essence of the invention. The particular wrench illustrated is constructed as follows:

The head of the wrench consists primarily of an integral, hollow, body member 10 constructed 40 of cast steel. Integrally connected with said body member is the usual long tapered handle 11, preferably of I beam cross section as shown. Said body member 10 is vertically bored out (on an axis perpendicular of the plane of movement 45 of the handle 11) to form a relatively long bearing 12 in which are rotatably arranged the two journals 13 and 131 of a rotatable ratchet head 14 (see Fig. 4). The latter is suitably enlarged at its lower end to form an annular shoulder 15 which prevents upward displacement of said 50 rotatable ratchet head relatively to the body member 10. Downward displacement of said rotatable ratchet head 14 is prevented by a screw collar 16 threaded onto the upper end of said ratchet head 14 and screwed tightly down against

the upper annular shoulder 17 of said ratchet head 14. This screw collar 16 is preferably of hexagonal or other flat faced shape so as to be readily turned by a wrench. When the same size of ratchet head 14 is used for a considerable period of time, it is desirable to very solidly clamp this screw collar 16 in its screwed down position, and this is effected in the present invention by splitting the screw collar 16 at 18 and clamping together the two ears 20 and 20a of said collar 10 with a cap screw 21.

The interior of said rotatable ratchet head 14 is coaxially cored or otherwise shaped to form a hexagonal or other desired form of flat faced socket 22 at its lower end so as to engage with 15 the nut or other object being turned by the wrench. The central and upper portion of said rotatable ratchet head 14 is suitably cored or drilled coaxially to form a cylindrical hole 23 to enable the socket 22 to engage the entire area 20 of the faces of the nut being turned, even though the threaded end of the bolt, upon which said nut is being screwed or unscrewed, extends a considerable distance above the upper face of 25 said nut. This cylindrical hole 23 is also useful in enabling the operator to drive out the nut when it becomes jammed in the socket 22.

The body member 10 is so cast as to provide an interior hollow portion or chamber 24 which is entirely enclosed by the metal of said body member 10 except where it opens into the central rear part of the bearing 12. This means that the extreme front portion 25 of said body member 10 is integrally connected with the rear portion 26 of said body member 10, and also integrally to the handle 11, by horizontal webs 27 and 271. This renders the body member 10 and the whole head of the wrench much stronger than wrenches of this general type as heretofore constructed.

Arranged within the chamber 24 of said body member 10 is a pair of ratchet dogs or pawls 28 and 28a. The tall ends of said pawls are of semi-cylindrical form and are received or seated within companion, open, semi-cylindrical grooves 30, 30a. The form of these semi-cylindrical, open 40 grooves is preferably less than half cylindrical so as to enable the same to be expeditiously formed by coring.

Interposed between the other flat face of each 50 of said pawls 28, 28a and the adjacent companion flat face 19 of the chamber 24 is a pair of sheet metal, curvilinear springs 31, 311 whose front ends are curled at 32 to abut against the 55 companion transverse wall 29 of said chamber 24.

(see Fig. 2). The rear ends of each of these pairs of springs 31, 311 rest against the rear portion of the outer face of its companion pawl 28 or 28a, and each pair of said springs is integrally connected with the rear end of a companion, sheet metal restraining plate 33. The latter is flat and rests at all times flat against the outer flat face of its companion pawl 28 or 28a. The extreme front end of each of said restraining plates 33 is hooked at 34 over the front end or nose of its companion pawl 28 or 28a. This arrangement prevents each restraining plate from moving rearwardly relatively to its companion pawl 28 or 28a.

10 15 The mathematical formula for the shape of the curvilinear springs 31, 311 has not been determined, said curve having been obtained by a purely empirical or "lay-out" method with the successfully attained object of preventing any slackness at any time in the pivotal or rocking joint between the rear ends of the pawls 28, 28a and their companion semi-cylindrical, open grooves 30, 30a.

20 25 The front end of the one or other of said pawls 28, 28a is adapted to engage with ratchet teeth 35 which are formed integrally and coaxially on the ratchet head 14 intermediately of the annular journals 13, 131 thereof. These ratchet teeth 35 do not extend as far out from the axis of rotation 30 of the rotatable ratchet head 14 as do the journals 13 and 131 at the upper and lower boundaries of said ratchet teeth. In other words, the cylindrical plane which intersects the outermost portions of said ratchet teeth 35 has a smaller diameter 35 than the diameter of said journals 13, 131. This enables said ratchet teeth to be considerably burred or otherwise distorted (from use or abuse) but preventing such burred portions from jamming against the bore of the bearing 12, and 40 thereby preventing the free rotation of the rotatable ratchet head 14 in the body member 10.

45 50 When either the one or the other of the pawls 28, 28a engages with said ratchet teeth 35, its rabbeted outer end engages simultaneously with a pair of said ratchet teeth 35. This rabbeted construction permits of ratchet teeth of small pitch, thereby enabling the pawl to "take hold" after the operator has only swung the handle 11 through a relatively small number of angular degrees. It is true (generally speaking at least) that a single, small pitched ratchet tooth is weaker than a single large pitched ratchet tooth. This, however, is compensated for in the present invention by having each pawl engage with a pair 55 of ratchet teeth simultaneously. This provides the strength that could have been obtained by the use of large pitched ratchet teeth, and, at the same time, the small pawl engaging movement of the small pitched ratchet teeth. In addition to 60 this a sturdy pawl and ratchet construction is effected by this arrangement without unduly thinning the metal wall between the root of the ratchet teeth 35 and the coaxial, cylindrical hole 23 of the rotatable ratchet head 14. Furthermore 65 70 the strength of the connection between either of the pawls and the ratchet teeth is fully developed because of the fact that each pawl is pushed inwardly at a central point from its companion restraining plate 33 by a pair of curvilinear springs 31, 311 located adjacent the edges of their companion pawls and hence far enough apart to prevent any cocking of the pawl.

75 It will be noticed that the inner rabbeted step or tooth of each pawl is undercut. This positively prevents the pawl from becoming disengaged after it has "taken hold". It will also be noticed that all of the longitudinal corners of each pawl are generously bevelled. This enables the pawl to properly seat itself and to swing squarely without possibility of interference from the fillets of the chamber 24.

80 Means are provided for simultaneously throwing one of the pawls 28, 28a out of engagement and then permitting the other pawl to swing inwardly into operative position under the influence of its companion curvilinear springs 31, 311. This is effected by means of a shipper 36 which is arranged in the chamber 24 intermediately of the inner faces of the pawls 28, 28a and vertically pivoted at 37 and 371 in the body member 10 and 15 manually actuatable by an exterior, shipper handle 38. It will be noted that no resilient means are necessary to hold this shipper 36 in its one or other position. This is because of the disposition of the flat faces 40, 40 and 41, 41 of said shipper 20 which contact with the inner, flat faces of the pawls, the effective leverage exerted against the one flat face 40 of said shipper being less than the effective leverage exerted against the other flat face 41 of said shipper, despite the difference in 25 spring pressures exerted against the pawls.

25 30 35 40 Downward displacement of the shipper 36 is prevented by a head 40 which also has the function of preventing dirt from entering the chamber 24 through the upper shipper bearing 37. Upward displacement of said shipper 36 is prevented by a retaining washer 41 which is countersunk in the lower face of the body member 10 and embraces a reduced shank 42 at the lower end of said shipper and bears upwardly against a shoulder 43 formed 35 at the upper terminus of said shank 42. Said retaining washer is held in place by riveting, at 44, the protruding lower end of said shank 42.

Operation

40 45 50 55 The operator applies the hexagonal socket 22 of the rotatable ratchet head 14 to the nut he desires to have turned. If the bolt to which this nut is applied happens to extend up above the upper face of said nut, it is accommodated in the cylindrical hole 23 of said ratchet head 14. If the operator desires to tighten said nut, he throws the shipper 36 to the position shown in the drawings. This throws the pawls 28 out of operation and the pawl 28a into operation. He then swings the handle 11 back and forth in the usual way until the nut is tightened. If he desires to unscrew a nut, he reverses the position of the shipper 36 thereby throwing the pawl 28a out of operation and the pawl 28 into operation.

60 65 70 75 80 85 90 95 If the operator desires to use the wrench for a different size of nut, he loosens the cap screw 21 and unscrews the screw collar 16. He then throws the shipper 36 to its central position which throws out both of the pawls 28 and 28a and thereby facilitates the removal of the rotatable ratchet head 14. He then removes said ratchet head and replaces it with one having the desired size and shape of socket 22. He then screws back the screw collar 16. If he expects to use any certain size and shape of ratchet head 14 for a considerable period of time, or for very arduous work such as for underwater work, he then tightens the cap screw 21 so as to clamp the screw collar 16 in position.

90 95 98 If either the ratchet head 14 or its screw collar 16, or either one (or both) of the pawls 28, 28a or its springs 31, 311 and retaining plate 33 should become fractured or warrant inspection, this can be effected, without removing the shipper 36. The

ratchet head 14 and screw collar can be removed as just described. To remove either one of the pawls 28, 28a and its companion springs 31, 31a and integral retaining plate 33, the ratchet head

5 14 is removed as above described and then the hook 34 pushed outwardly away from the nose of its companion pawl 28 or 28a. The latter can then be easily slid forwardly through the chamber 24 and out through the bearing 12. The 10 springs 31, 31a with their integral restraining plate 33 can then be dropped out in the same way.

I claim as my invention:

1. A ratchet wrench comprising: a body member having a socket; a rotatable ratchet head 15 journaled in said body member and having ratchet teeth; a pawl disposed at its rear end within said socket and adapted to engage at its front end with said ratchet teeth; and restraining means for holding the front end of the pawl 20 in engagement with the ratchet teeth and the rear end thereof in engagement with the bottom of said socket comprising a plate engaging with the outer side of said pawl and bearing against the front end thereof and two curved 25 springs connected integrally with opposite edges of said plate and bearing both lengthwise and laterally against said body.

2. A ratchet wrench comprising: a body member having a socket; a rotatable ratchet head 30 journaled in said body member and having ratchet teeth; a pawl disposed at its rear end within said socket and adapted to engage at its front end

with said ratchet teeth and having a flat face; a restraining plate arranged against said flat face and hooked over the outer end of said pawl; and a curvilinear spring connected to said restraining plate and bearing with its outer end both laterally and longitudinally against said body member.

3. A ratchet wrench comprising: a body member having a socket; a rotatable ratchet head journaled in said body member and having ratchet teeth; a pawl disposed at its rear end within said socket and adapted to engage at its front end with said ratchet teeth and having a flat face; a restraining plate arranged against said flat face and hooked over the outer end of said pawl; and a curvilinear spring connected to said restraining plate and having a curled foot at its outer end bearing both laterally and longitudinally against said body member.

4. A ratchet wrench comprising: a body member having a handle and an open socket; a rotatable ratchet head journaled in said body member and having ratchet teeth; a pawl seated at its rear end in said open socket and adapted to engage at its front end with said ratchet teeth; and means abutting both lengthwise and transversely against said body and also engaging with the front end of said pawl for holding the latter against said ratchet teeth and also holding the same in said socket.

FOSTER A. HAIST.
